UNITED STATES PATENT OFFICE.

FRANK VOIGTMANN AND SILAS H. POMEROY, OF CHICAGO, ILLINOIS.

FIREPROOF WINDOW.

SPECIFICATION forming part of Letters Patent No. 657,996, dated September 18, 1900.

Application filed February 5, 1900. Serial No. 4,102. (No model.)

To all whom it may concern:

Be it known that we, FRANK VOIGTMANN and SILAS H. POMEROY, citizens of the United States, residing at Chicago, in the county of 5 Cook, State of Illinois, have invented a new and useful Improvement in Fireproof Windows, of which the following is a specification.

Our invention relates to that class of windows in which the sash and casing are made of fireproof material and in which the sash is made to close automatically when the fire strikes it.

It consists of details hereinafter fully described, and particularly pointed out in the claims.

Figure 1 is a perspective view of our window from the interior. Fig. 2 is a longitudinal sectional view through the upper portion. 20 Fig. 3 is a detail view of the weight removed. Fig. 4 is a cross-section of the upper portion.

A represents the casing; B B', the sash; C, the cord; D, the pulleys; E, the weight, and F the fusible plug.

25 The casing is made of fireproof material, preferably galvanized iron. The sashes are made of similar material and slide up and down in the casing, one being made to balance the other, the cords C being attached to both sashes near their edges and passing over 30 the pulleys D at each side. In this way the sashes open and close together, one moving with the other.

The weight E is suspended in the casing, 35 above the lower sash, by means of a fusible plug F. In case of fire the plug is melted and the weight allowed to fall upon the sash, bearing it down, if it happens at the time to be raised, and automatically closing it and at the 40 same time the other sash, with which it is connected through the cord and pulleys.

The fusible plug is made in any suitable manner which will release the weight on the occurrence of undue heat, but preferably consists of a vertical portion a, which is attached to the casing by a bolt b and which extends through the weight and has the cross-piece c attached to it below the weight by a fusible solder, which latter will melt off when the heat 45 strikes it and allow the weight to slide over a and down along the cords at each end, which run in the guides e e in the weight.

We have shown our invention as applied

to a window in which the two sashes are made to balance one another and in which a case- 55 ment-sash G is hinged in the sliding sash at its outer edges on hinges g.

The hinged sash is designed to be used chiefly for convenience in cleaning the windows from the inside and at other times to be 60 kept closed and locked, as at h.

It is obvious that instead of applying our invention to the two sliding sashes connected one with the other, as shown above, it may be applied to the lower one of the ordinary 65 sliding sashes in which a sash-weight is used, the weight which is released being sufficient to overbalance the sash-weight and to force down the sash.

What we claim, and desire to secure by Letters Patent, is—

1. The combination of the fireproof casing A, the fireproof sash B, sliding therein, the weight E, located above said sash, and the destructible retaining device F, by which said weight is released when fire reaches it; all 75 substantially as shown and described.

2. The combination of the fireproof casing A, the fireproof sash B sliding therein, the weight E, located above said sash, and the 80 fusible plug F, located in an exposed position, by which said weight is released when the fire reaches said plug; all substantially as shown and described.

3. The combination of the fireproof casing 85 A, the fireproof sash B, sliding therein, the weight E, located above said sash, having the guides e e at each end for the sash-cords, and the fusible plug F, by which said weight is held in place; all substantially as shown and 90 described.

4. The combination of the fireproof casing A, the fireproof sashes B, B' sliding therein, the cords C, C, connecting said sashes, the pulleys D, D over which said cords pass, the 95 weight E located so as to fall upon one of said sashes when released, and the destructible retaining device F by which said weight is suspended; all substantially as shown and described.

FRANK VOIGTMANN.
SILAS H. POMEROY.
